UNITED STATES PATENT OFFICE.

EMIL C. COLLIARD, OF ARCADE, NEW YORK.

CHARGE-FORMING DEVICE FOR INTERNAL-COMBUSTION ENGINES.

Application filed March 12, 1924. Serial No. 698,741.

The object of the invention is to provide a charge forming device for internal combustion engines which is especially designed for use on motor vehicles such as automobiles or the like, and which operates to increase the mileage obtained per gallon of gasoline or other fuel used, while providing for easy starting and flexibility of operation and enhancing the power of the engine and decreasing or minimizing the formation of carbon in the engine.

A further object is to provide a device of this character having the foregoing enumerated advantages and capacities and which is also of simple and durable construction and well adapted for easy and comparatively inexpensive manufacture and installation on the various types of automobiles or motor vehicles.

Other objects and advantages reside in the certain novel features of the construction, combination and arrangement of parts, which will be hereinafter more fully described and particularly pointed out in the appended claims forming a part of this specification, reference being had to the accompanying drawings also forming a part of this specification, and in which:

Figure 1 is a view in side elevation showing the invention applied to an automobile,

Figure 2 is a fragmentary view in section showing the combined heating and mixing chamber and the associated parts,

Figure 3 is a fragmentary view in elevation showing the hand operated control lever for the valve of the device,

Figure 4 is a fragmentary and diagrammatic perspective view showing the general features of the assembly,

Figure 5 is a detail view in section of the liquid trap employed, and

Figure 6 is a detail view in section showing the connection to the intake manifold.

Referring to the drawings the numeral 10 designates an automobile having an engine 11 of the internal combustion type and including along with the other instrumentalities ordinarily employed an intake manifold 12, an exhaust manifold 13, a water cooling system designated generally at 14 and embodying a vapor space 15 above the radiator thereof, and the gasoline or fuel supply tank 16.

The charge forming device which constitutes the present invention includes a combined heating and mixing chamber

designated generally at 17. This chamber includes a cylindrical body portion 18 having an integral dome-shaped head 19 at its upper end. A removable head 20 closes the lower end of the chamber and has integrally formed therewith a depending and an externally threaded stud 21 engaged with a correspondingly threaded bearing or opening 22 formed in the exhaust manifold 13 whereby the chamber 17 is supported. This arrangement also provides for heating the chamber 17 since the stud 21, the head 20 and the body portion of the chamber are made of metal having a high degree of heat conductivity. Within the body portion 18 of the chamber 17 a screen 23 is pressed or otherwise suitably secured. This screen 23 defines within the chamber 17 a mixing space 24 in the lower end of the chamber and an outlet space 25 in the upper end of the chamber.

A connection is provided between the fuel supply tank 16 and the mixing space 24 of the chamber 17, this connection being designated at 26. Preferably the connection 26 takes the form of flexible copper tubing, although of course any suitable connection may be employed. One end of the connection 26 is suitably coupled as at 27 to the top of the fuel supply tank 16 so that the connection will draw the fuel laden vapor from the fuel supply tank. The opposite end of the connection 26 is suitably coupled to one side of the lower portion of the chamber 17 so that the connection communicates with the mixing space 24 of the chamber. Obviously the conventional compression couplings may be used wherever it is necessary to connect the copper tubing to the other instrumentalities employed. A liquid trap designated generally at 29 is embodied in the connection 26, the tubing making up the connection being provided in sections for this purpose. The trap 29 is shown in detail in Figure 5 and consists of a container or closed housing 30 having a portion 31 disposed at a level lower than the lowermost point in the connection 26. A removable drain plug 32 may be provided in the trap 29. With this arrangement should any liquid be drawn through the connection 26 it will collect in the trap 29.

A connection is provided between the mixing space 24 of the chamber 17 and the vapor space 15 of the cooling system 14, and is designated generally at 35. This connection

35 also takes the form of flexible copper tubing having one end coupled as at 36 to the radiator of a cooling system and then extended vertically up through the vapor space at the top of the radiator to a point above the highest level of the water or cooling fluid. The connection 35 is also connected to the lower portion of the mixing chamber 17 so as to communicate with the mixing space 24 of said chamber. Preferably the connections 26 and 35 are coupled to the opposite sides of the chamber 17.

A T 40 is arranged above the chamber 17 and has one of its arms threadedly engaged as at 41 with the dome-shaped head 19 of said chamber. The horizontal arms of the T are alined and in one of these arms a valve seat 42 is provided. A valve 43 co-acts with the valve seat 42 and has a stem 44 integral therewith and slidably fitted in a guide opening 45 provided in a cap nut 46 threadedly engaged with the T 40. A compression coil spring 47 encircles the valve stem 44 and abuts the cap nut 46 at one end and the valve 43 at its opposite end, whereby the spring tends to urge the valve to closed position and to yieldably maintain the same in such position. It is proposed to open the valve from the dashboard of the vehicle, and for this purpose a wire or other suitable flexible connecting element such as is designated at 48 is provided and has one end fastened to the valve stem 44 and has its opposite end fastened to an operating rod 49 slidably and rotatably fitted in a bearing sleeve 50. The bearing sleeve 50 extends from the dashboard of the vehicle and is externally threaded, whereby it may be held to the dashboard by means of nuts 51 and washers 52. A longitudinal groove designated at 53 is formed in the sleeve 50 and in this groove the pin 54 rigidly secured to the operating rod 49 is slidably fitted. With this arrangement the rod 49 may be pulled upwardly and outwardly with respect to the sleeve 50 and after it has been pulled to such an extent as to move the pin 54 out of the slot 53, the rod is rotated to engage the pin 54 with the nut 51 at the extreme upper end of the sleeve 50. Of course this nut 51 at the extreme upper end of the sleeve 50 may be formed integral with the sleeve as it is necessary to have only one nut or dashboard engaging element threaded onto the sleeve. In order to provide for the automatic return of the rod 49 when it is rotated so as to bring the pin 54 into alinement with the groove 53, a spring 55 is arranged on the lower end of the rod and has one end engaging the lower end of the sleeve 50 and its opposite end engaging a cotter pin 56 fastened in a transverse aperture provided at the lower extremity of the rod 49. This arrangement provides a spring closed valve which is however, manually operable

from the dashboard of the vehicle by the driver of the vehicle. It is to be understood that the valve is manually operable in the sense that it may be opened to the desired degree by simply pulling upwardly and outwardly on the operating rod 49. Of course the valve may be held open by pulling the pin 54 out of the groove 53 and rotating the operating rod to engage this pin 54 with the nut or head 51 provided at the extreme upper end of the sleeve 50.

A flexible copper tubing 60 is connected to the T 40 by a compression coupling 61 and extends to the intake manifold 12. The end of the copper tubing 60 which is disposed adjacent the intake manifold has secured thereon an inlet nipple 62 which extends into the intake manifold 12. The portion of the inlet nipple 62 lying within the manifold 12 is formed with a plurality of 85 perforations or discharge orifices 63. Obviously the T 40, the flexible tubing 60 and the inlet nipple 62 together with the couplings for connecting these elements together and to the associated instrumentalities provide a connection between the mixing chamber and the intake manifold.

It is of course to be understood that the engine is to be provided with the usual carbureter and other devices for supplying a combustible charge to the engine cylinders as well as with the charge forming device constituting this invention. It may be found however that the charge forming device will permit the elimination of the carbureter and associated instrumentalities, but in the preferred application of the invention the carbureter and other devices are employed.

When the engine is running and the valve 43 engaged with the seat 42, that is, when the valve 43 is closed, the charge forming device is not in operation, since the suction in the intake manifold is not exerted in the outlet space 25 of the chamber 17. When, however, the valve 43 is open the suction exerted through the inlet nipple 63 and tubing 60 will draw fuel laden vapor from the gasoline supply tank 16 through the connection 26 into the mixing space 24 and it will also draw moisture laden vapor through the connection 35 from the vapor space 15 of the tubing system. In the mixing space 24 of the chamber 17, the fuel laden vapor and the moisture laden vapor will commingle 120 and these commingled vapors will pass up through the screen 23 into the outlet space 25, from whence they flow through the T 40 and tubing 60 to the inlet nipple 63. The vapors issue from the perforations of the nipples 63 in the form of a multiplicity of finely divided jets. It has been found that with this arrangement a great saving is had in the consumption of gasoline or other fuel, and an increased mileage per gallon of 130

fuel is the result. This advantage is had along with a flexibility of operation not approached in the ordinary motor. Moreover the power of the motor is increased and the liability of carbon accumulating is minimized if not obviated. In addition to these advantages starting is made easy even in cold weather for if the valve 43 is open when the engine is turned over, the mixture drawn from the carburetor is enriched and rendered more highly combustible by the commingled vapors fed into the intake manifold in the manner hereinabove described.

I claim:

- 15 1. In combination with an internal combustion engine having an intake and an exhaust manifold, a water cooling system having a vapor space, and a main fuel supply tank, a combined heating and mixing chamber associated with the exhaust manifold so as to be heated thereby, a connection between the main fuel supply tank and the chamber, said connection communicating with the main fuel tank at a point above the level of the fuel therein, and having a liquid trap therein, a connection between the chamber and the vapor space of the water cooling system, and a connection between the chamber and the intake manifold.
- 20 2. In combination with an internal combustion engine having an intake and an exhaust manifold, a water cooling system having a vapor space, and a main fuel supply tank, a combined heating and mixing chamber associated with the exhaust manifold so as to be heated thereby, a connection between the main fuel supply tank and the chamber, said connection communicating with the main fuel tank at a point above the level of the fuel therein, a connection between the chamber and the vapor space of the water cooling system, a connection between the chamber and the intake manifold, and a manually operable valve in the connection between the chamber and the intake

manifold, said valve being spring closed and being adapted to be operated from the dashboard of the vehicle.

3. In combination with an internal combustion engine having an intake and an exhaust manifold, a water cooling system having a vapor space and a main fuel supply tank, a combined heating and mixing chamber associated with the exhaust manifold so as to be heated thereby, a screen within the chamber defining a mixing space and an outlet space within the chamber, a connection between the main fuel supply tank and the mixing space in the chamber, said connection communicating with the fuel tank at a point above the level of the fuel therein, a connection between the mixing space in the chamber and the vapor space of the cooling system, and a connection between the outlet space of the chamber and the intake manifold.

4. In combination with an internal combustion engine having an intake and an exhaust manifold, a water cooling system having a vapor space and a main fuel supply tank, a combined heating and mixing chamber of hollow construction having a solid externally projecting stud directly and positively engaged with the exhaust manifold, said chamber and said stud being of relatively high heat conductivity so as to provide for the exchange of heat between the exhaust manifold and the chamber as well as to afford a mounting for the combined heating and mixing chamber, a connection between the main fuel supply tank and the chamber, said connection communicating with the main fuel supply tank at a point above the level of the fuel therein, a connection between the chamber and the vapor space in the water cooling system, and a connection between the chamber and the intake manifold.
